UNITED STATES PATENT OFFICE

107,094

DESIGN FOR A COMBINET

John Gordon Rideout, Cleveland, Ohio, assignor to Columbian Enameling & Stamping Co., Inc.,
Terre Haute, Ind., a corporation of Indiana

Application June 30, 1937, Serial No. 70,178

Term of patent 7 years

To all whom it may concern:

Be it known that I, John Gordon Rideout, a citizen of the United States, residing at Cleveland, in the county of Cuyahoga and State of Ohio, have invented a new, original, and ornamental Design for a Combinet, of which the following is a specification, reference being had to the accompanying drawing, forming part thereof.

Fig. 1 is a top plan view of a combinet showing my new design;

Fig. 2 is a view in front elevation thereof.

I claim:

The ornamental design for a combinet as shown.

JOHN GORDON RIDEOUT.
